UNITED STATES PATENT OFFICE.

ROBERT HOPE-JONES, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

ORGAN-SWELL

1,021,149.

Specification of Letters Patent. Patented Mar. 26, 1912.

Application filed July 28, 1910. Serial No. 574,248.

To all whom it may concern:

Be it known that I, ROBERT HOPE-JONES, a subject of the King of England, residing at North Tonawanda, in the county of 5 Niagara and State of New York, have invented new and useful Improvements in Organ-Swells, of which the following is a specification.

One of the objects of my invention is the 10 provision of simple means in convenient sight of the performer for indicating at all times the position of the swell-box-shutters.

A further object is to effect the movements of the swell-shutters by a motor under the control of the performer so as to 15 facilitate the operation and improve the action of the shutters, this feature in the preferred form of the invention being combined with said indicator as well as with 20 the usual swell pedal, so that the motor may be manually controlled by means of the indicator when the feet are used upon the bass pedals or are otherwise engaged.

In the accompanying drawings consisting 25 of 2 sheets: Figure 1 is a front view of a pipe organ embodying the invention. Fig. 2 is a fragmentary vertical section of the electro-magnetic brake coöperating with the shutter-operating motor, showing the brake applied. Fig. 3 is a side elevation of said 30 brake in the same position. Fig. 4 is a transverse section on line 4—4, Fig. 3. Fig. 5 is a diagrammatic sectional elevation of the organ showing the position of the parts 35 when one of the swell indicators and manual motor-controllers is depressed. Fig. 6 is a fragmentary sectional elevation of the electric switch controlled by said indicator. Fig. 7 is a transverse vertical section on 40 line 7—7, Fig. 6 showing the switch spring in its normal central position.

Similar letters of reference indicate corresponding parts throughout the several views.

45 A indicates the swell-pedals preferably pivoted to rock in a vertical plane in the usual manner; A¹ one of the swell-boxes having the usual pivoted shutters A²; A³ the actuating arms of the shutters, and A⁴ 50 the link connecting the several arms. In the construction shown in the drawings, the pedal is connected with the vertical link A⁴ by the usual pedal-arm a, links a¹, a² and bell crank a³.

Arranged at the front of the console, 55 preferably immediately below the desk B, is a series of swell indicators C, one for each swell-box, which take part in the movements of the swell-shutters and thus serve to visually indicate their position. These 60 indicators may be of any suitable construction, but preferably consist of vertically swinging levers, the front arms of which extend forwardly through a fixed slotted bar c and terminate in knobs, as shown, 65 while the rear arm of each lever is connected with the operating link a² of the corresponding swell-shutter by a sectional connecting rod d, d¹ and a bell crank d². Obviously the indicator levers may be connected with any other member of the connecting train between the swell-pedals and the shutters, or with the pedals themselves. It will now be understood that when the 70 shutters are opened more or less, the exposed front arm of the corresponding indicator C is depressed accordingly, as shown by full lines in Fig. 5, while when the shutters are closed, said arm is correspondingly raised, thus indicating to the performer by a convenient forward glance the 75 position of the shutters and avoiding the necessity of looking down at the pedals for that purpose. These indicators are also 80 preferably used for manually controlling a suitable shutter operating motor. This motor is preferably of an electro-pneumatic character and constructed as follows: E, E¹ indicate a pair of oppositely and alternately-acting motor pneumatics secured to 85 opposite sides of a pressure or wind chest F and having the arms e of their movable boards connected with the link a² by short links e¹, so that the alternate inflation of 90 said pneumatics causes the swell-shutters 95 to be opened and closed. Each of these pneumatics connects by a channel f with a vertical port f¹ which opens at its lower end into the atmosphere and at its upper end into the main pressure chamber F¹ of the wind 100 chest which has the pressure inlet f² connected with a source of compressed air not shown in the drawings. The upper and lower ends of each port f¹ are controlled 105 by pressure and exhaust valves f³, f⁴ both mounted on a stem f⁶. The latter is connected to the vertically-movable lower board of a pneumatic f⁶ located in the wind chest

and which when collapsed by the pressure (see right hand pneumatic) opens the pressure valve f^3 and closes the exhaust valve f^4 , thereby admitting pressure to the corresponding motor pneumatic E or E^1 and operating the swell-shutters accordingly. Each of these valve operating pneumatics is connected by a channel g with a valve chamber g^1 which communicates constantly with the wind chest by a pressure port g^2 and with the atmosphere by an exhaust port g^3 controlled by a valve g^4 . The valves g^4 constitute or are carried by armatures which coöperate with electro-magnets h , h^1 . When either of these magnets is energized, it attracts the corresponding valve g^4 , opening the exhaust port g^3 and closing the pressure port g^2 , whereupon the corresponding valve operating pneumatic is collapsed by the wind chest pressure and the air is exhausted from said pneumatic through the channel g and port g^3 . When the magnet is de-energized, the wind chest pressure moves the valve away from the magnet, opening the pressure port g^2 and closing the exhaust port g^3 . Pressure is now admitted to the corresponding valve-operating pneumatic f^6 , inflating the latter, and reversing the valves f^3 , f^4 to the position in which the air is exhausted from the corresponding motor pneumatic E .

The magnets h , h^1 are included in separate electric circuits controlled by a switch which is preferably operated by the corresponding indicator C , so that when the latter is depressed one of said circuits is closed, while when it is raised the other circuit is closed, thus alternately energizing the magnets and causing the motor pneumatics E , E^1 to open or close the swell-shutters. This switch may be of any suitable construction. In the construction and arrangement shown in the drawings, the lower connecting rod section d^1 is provided at its upper end with a pair of spaced horizontal contacts or bars i , i^1 each forming a terminal of one of the magnet circuits. Between these contacts is arranged a switch or switch-spring i^2 forming the other terminal of both of said circuits and adapted to touch one or the other of the terminal contacts i , i^1 for closing either of the circuits. The ends of this switch spring are clamped between non-conducting blocks i^3 which insulate said contacts, while its free central portion is attached to the forked lower end of the upper connecting rod section d by a transverse pin i^4 . By this construction the two rod sections d , d^1 are yieldingly connected by the switch spring which latter is so stiff as to remain normally out of contact with the terminals i , i^1 .

The corresponding indicator lever C is so light compared with the resistance of the switch-spring that the latter remains prac-

tically undeflected and compels the indicator-lever to follow the movements of the rod-sections d , d^1 to indicate the position of the shutters. When, however, an indicator-lever is depressed by the performer, the switch spring, owing to the resistance of the relatively heavy shutters and the brake herein-after described yields upward sufficiently to touch the upper contact terminal i , as shown in Fig. 5, thus closing the circuit of the magnet h^1 , admitting pressure to the right hand motor pneumatic E^1 and causing the latter to open the shutters as hereinbefore described. To close the shutters by means of said manually controlled operating mechanism the indicator lever is thrown to the elevated position shown by dotted lines in Fig. 5, thereby deflecting the switch spring i^2 downward into contact with the lower circuit terminal i^1 , as shown by full lines in Fig. 6, and closing the circuit of the other magnet h . Pressure is now admitted to the corresponding motor pneumatic E which thereupon shifts the shutter connections in the proper direction to close the shutters.

In the magnet circuits shown in the drawings the switch spring i^2 is connected with one electrode of the battery J by a conductor j . A conductor j^1 leads from the other electrode to one end of each magnet-coil, while the other ends of said coils are respectively connected with the contact terminals i , i^1 by conductors j^2 , j^3 . These particular circuits are however, shown by way of example only and obviously may be changed without departing from the spirit of the invention.

In order to prevent overthrow or excessive movement of the shutters by the motor pneumatics, a brake is employed which promptly arrests the movement of the shutters when either of the magnet circuits is broken. This brake is preferably constructed as follows: k , k^1 indicate a pair of brake shoes acting against opposite sides of the link a^2 or equivalent member of the shutter-operating mechanism and hinged at their inner ends to a wind chest L or other support, as shown at k^1 . These shoes are normally retracted to release said link, by a suitable spring k^2 and are applied by a pair of motor pneumatics M , the movable boards of which carry lugs m which bear against the backs of the brake shoes, so that the latter are forced against the link a^2 by the inflation of said pneumatics. The latter are connected by ducts n with a common channel n^1 leading to a valve chamber N which communicates with the atmosphere by a port n^2 and with the pressure chamber of the chest L by a port n^3 . These ports are controlled by a double-faced valve o which when in the lowered position shown in Fig. 2 admits pressure to the brake-pneumatics M and causes them to apply the

brake shoes, while when the valve is in its raised position, as shown in Fig. 5, it allows the air to exhaust from the said pneumatics, permitting the spring k^2 to withdraw the 5 brake-shoes. The valve o is reciprocated by a pair of oppositely-acting pneumatics p , p^1 arranged within the wind chest L and having their movable boards suitably connected with the stem of the valve. Each of these 10 valve operating pneumatics is connected by a channel q with a valve chamber q^1 which communicates constantly with the wind chest L by a pressure port q^2 and with the atmosphere by an exhaust port q^3 controlled 15 by a valve q^4 . The valves q^4 are in the form of armatures which coöperate with electro-magnets q^5 , q^6 . The operation of this electro-pneumatic action is the same as that of the motor pneumatics E , E^1 except that 20 when one of the magnet circuits is closed the valve o connects the brake-shoe pneumatics with the atmosphere and cuts them off from the wind chest, this valve being lowered to the position shown in Fig. 2, by 25 the pressure in the wind chest.

The brake-controlling magnets q^5 , q^6 are connected with the circuits of the other magnets h , h^1 by conductors r , r^1 , r^2 , so that the brake circuit is closed simultaneously 30 with the shutter-operating circuits by the manual depression or elevation of the corresponding indicator C .

Normally the several circuits are open and the valve o is in its lowered position. 35 Under normal conditions with pressure in the brake wind-chest, the brake pneumatics M are inflated and the brake shoes are applied. Upon closing the circuits either by depressing or returning one of the indicators and controllers C , the brake circuit is closed, deflating the pneumatics M , withdrawing the brake shoes and permitting the shutter-pneumatics E , E^1 to freely operate the shutters. As soon as the indicator 45 is released by the performer, the brake circuit is broken and the brake-shoes are promptly applied, holding the shutters in the desired position and also offering the necessary resistance to deflect the switch-spring i^2 .

The shutter-operating motor and the brake are controllable by the pedals A as well as the indicators C . For this purpose, a suitable switch is combined with each pedal or 55 with the operating connections between the same and the shutters. In the example shown in the drawings, each pedal is provided on its upper side, on opposite sides of its pivot, with insulated contacts s , s^1 which 60 coöperate with switch-contacts t , t^1 carried by a rocking switch or foot plate T overlying the pedal and mounted upon the pedal-pivot by means of a lug t^2 passing through an opening in the pedal. As shown, the foot 65 pedal contact s is connected with the con-

ductor j^3 and the coöperating switch contact t is connected with the conductor j by a conductor t^3 . The pedal contact s^1 is connected with the conductor j^2 , while the coöperating switch contact t^1 is connected with the conductor t^3 . Thus, upon rocking the switch plate T to connect the contacts s and t , the circuits including the shutter-controlling magnet h^1 and brake releasing magnet q^6 , are closed and the shutters are opened, 70 while upon rocking said plate in the opposite direction to connect the contacts s^1 and t^1 , the circuits including the other shutter controlling magnet h and brake releasing magnet q^5 are closed, turning the shutters 75 into their closed position.

When the switch plate T is parallel with the pedal, neither of its contacts touches those of the pedal. The plate is yieldingly held in that normal position by springs u 80 interposed between the plate and the pedal on opposite sides of the switch-plate pivot and preferably consisting of rubber blocks or buttons, as shown.

By the construction just described, the 85 organist has full control of the swell shutters by the use of the pedal aided by the shutter-operating motors E , E^1 . When it is desired to open the shutters partly, the player momentarily depresses the toe-portion of the switch plate T to bring the shutter-opening motor E into action, and then by rocking the switch plate in the opposite direction, the shutter-closing motor E^1 comes 90 into action and opposes the motor E , preventing the latter from fully opening the shutters. In a similar manner, the complete closing of the shutters may be prevented. At the same time, the indicator C 95 constantly and accurately shows the position of the shutters.

I claim as my invention:

1. In an organ, the combination of a swell-box, its shutters, means for operating the shutters, and an indicator controlled by the 100 shutter operating means to indicate the position of the shutters.

2. In an organ, the combination of a swell-box, its shutters, means for operating the shutters, and an indicator operatively connected with the shutter operating means.

3. In an organ, the combination of the key boards, a swell-box, its shutters, operating mechanism for the shutters, a visual indicator arranged above the key-boards, and means for operatively connecting the indicator with the shutter-operating mechanism.

4. In an organ, the combination of the key-boards, a swell-box, its shutters, operating mechanism for the shutters, a vertically swinging indicator lever arranged above the key boards, and means for operatively connecting said lever with the shutter-operating mechanism.

5. In an organ, the combination of a swell-

box, its shutters, a motor for operating the shutters, and a combined indicator and controller operatively connected with the shutters and controlling said motor.

5 6. In an organ, the combination of a swell box, its shutters, a motor for operating the shutters, a brake for arresting the movement of the shutters, and a combined indicator and controller operatively connected with 10 the shutters and controlling said motor and said brake.

7. In an organ, the combination of a swell-box, its shutters, a motor for operating the shutters, including a power-pneumatic connected with the shutters, valve mechanism controlling the passage of the air to and from said pneumatic, a circuit containing an electro-magnet which controls said valve mechanism, a combined indicator and controller operatively connected with the shutters, and a switch controlling said magnet-circuit and operated by said indicator and controller.

8. In an organ, the combination of a swell-box, its shutters, an electro-pneumatic motor for operating the shutters, a circuit including said motor, a combined indicator and controller, a connection between said indicator and the shutters, said connection including relatively-movable parts, one of which carries an electric contact forming a terminal of said circuit, and a switch-member carried by the other of said parts and coöperating with said contact, said switch-member being operatively connected with 35 said indicator and controller.

9. In an organ, the combination of a swell-

box, its shutters, an electro-pneumatic motor for operating the shutters, a circuit including said motor, a combined indicator and controller, a connection between said indicator and the shutters, said connection including relatively-movable parts, one of which carries a pair of spaced contacts included in said circuit, and a switch-spring carried by the other of said parts, arranged between said contacts and forming a terminal of said circuit, said spring forming a yielding connection between said relatively-movable parts and being operatively connected with said indicator and controller.

10. In an organ, the combination of a swell-box, its shutters, a motor for operating the shutters, including a power-pneumatic connected with the shutters, valve mechanism controlling the passage of the air to and from said pneumatic, and an electro-magnet controlling said valve mechanism, means for arresting the movement of the shutters including a brake-shoe, a power pneumatic for actuating said shoe, valve mechanism controlling the passage of the air to and from said pneumatic, and an electro-magnet controlling said valve mechanism, said brake-shoe pneumatic being arranged to normally apply the shoe, and a circuit including said electro-magnets and a controlling switch.

Witness my hand this 25th day of July, 1910.

ROBERT HOPE-JONES.
